GYRATORY CRUSHER

John H. Spohn, Jr., San Francisco, Calif.

Application November 6, 1937, Serial No. 173,159

8 Claims. (Cl. 83—10)

This invention relates generally to machines of the type commonly known as gyratory crushers, which make use of a gyrating pestle disposed within a stationary bowl. Such machines have application to a wide variety of crushing and grinding operations, including the crushing of metallurgical ore.

It is an object of the invention to provide a machine of the above character in which the pestle and cooperating bowl can be readily cleaned, with a minimum of time and effort. The machine is therefore particularly suited for assay operations, where it is necessary to carefully remove all particles of ore adhering to the working parts, between the crushing and grinding of various samples.

A further object of the invention is to provide a machine which will have a greater range of application than machines heretofore available. By range of application I have particular reference to use of the machine on ore consisting of both large and small sized fragments, whereby in many instances preliminary crushing operations may be simplified or omitted.

Another object of the invention is to provide a novel form of combined gyratory and attrition mill, in which the attrition mill also receives gyratory movement, to facilitate fine grinding operation.

Further objects of the invention will appear from the following description in which the preferred embodiment of the invention has been set forth in detail, in conjunction with the accompanying drawing.

Referring to the drawing:

Fig. 1 is a side elevational view, in cross-section illustrating one embodiment of the present invention.

Fig. 2 is a cross-sectional view taken along the line 2—2 of Fig. 1.

Fig. 3 is a cross-sectional view taken along the line 3—3 of Fig. 1.

Fig. 4 is a cross-sectional view taken along the line 4—4 of Fig. 2.

The machine as illustrated in the drawing consists of a base structure 10, which carries the structural uprights 11. Mounted on this base there is a bowl structure designated generally at 12, and this structure surrounds the pestle 13.

The pestle 13 can be contoured in the manner illustrated, and it is journalled upon the upright spindle or shaft 14. Gyratory movement is imparted to the upper end of the pestle 13, by eccentric means designated generally at 16. In the embodiment illustrated this eccentric means

makes use of a drive wheel 17, supported by the ball bearing assembly 18, which in turn is carried by the portion 19 connecting the uprights 11. Concentrically disposed within the fly wheel 17, there is a sleeve 21, which is shown provided with a hand wheel 22, to facilitate manual adjustment. A threaded engagement 23 connects the sleeve 21 with the fly wheel 17, whereby upon turning the hand wheel 22, the sleeve 21 is adjusted in a vertical direction. The upper end of pestle 13 is fixed to a bushing 24, which in turn is journalled within the lower eccentric portion 26 of the sleeve 21. Bushing 24 has an upper shoulder 27, whereby it is supported by the sleeve 21. The upper end of bushing 24 is engaged by the lower end of a compression spring 28, whereby the bushing 24 and the associated pestle 13 are urged downwardly. The lower end of shaft 14 is carried by an adjustable thrust block 31, the mounting for which will be presently described. It will be apparent that upon turning fly wheel 17, by virtue of a drive connection to some suitable source of power, the pestle 13 is gyrated and also gyratory movement is imparted to the spindle 14.

In many instances the pestle 13 and bowl can be used without an associated attrition mill. However, for certain applications, as for example assay work, it is desirable to carry the grinding to a further degree of fineness, by the use of an attrition mill. Thus in the embodiment illustrated, an attrition mill is provided which includes a rotor 32, fixed to the spindle 14 below the pestle 13. The upper end of the rotor 32 has a projecting sleeve 33, which slidably fits a bore 34 formed in the lower end of the pestle. The upper grinding face 36 of the rotor 32, is convex and substantially spherical. This working face of the rotor cooperates with a convex and substantially spherical grinding face 37, provided by the bowl structure 12.

It will be evident that as the pestle is gyrated, rotor 32 will likewise be gyrated with respect to the bowl structure. However instead of permitting rotation of the rotor in the manner similar to the pestle, the rotor is positively driven. Thus the upper end of shaft 14 is provided with a drive wheel 38, which can connect by a drive belt or other suitable means to a source of power.

The bowl structure 12 is divided on a vertical plane, to form the two sections 12a and 12b. The lower ends of these sections have hinge connections 39 with the base structure 10, thereby making it possible for these sections to be swung outwardly and downwardly to positions such as

illustrated in dotted lines in Fig. 1. In order to clamp the two sections together, during normal operation of the machine, the sections are both provided with side flanges 41, positioned upon opposite sides of the webs 42, the latter being formed on the uprights 44. Suitable clamping means, such as bolts 43, extend through the flanges 41 and webs 42. It will be apparent that other types of clamping means can be utilized if desired, to facilitate rapid clamping and unclamping.

The contouring of the pestle illustrated in the drawing, and also the contouring of the cooperating surfaces formed by the bowl structure, is desirable and will give satisfactory results. Briefly the pestle is generally pear shaped. The plane 1 corresponding to its maximum diameter, is near the lower end of the pestle and below this plane the pestle is substantially spherical and convex. Above plane 1 the pestle converges upwardly, initially at a rapid rate, and then more gradually for the upper part of the pestle.

Below the plane 1 the cooperating surfaces of the bowl structure indicated generally at 46, are convex and substantially spherical, and generally symmetrical with respect to the axis of gyration of the pestle. Above the plane 1 the bowl continues to be symmetrical about the axis of gyration of the pestle, until about the region of the plane 2. Note that there is an undercutting to the bowl below the plane 2, or in other words between planes 1 and 2 and extending entirely about the pestle. This undercutting tends to generally urge the pestle downwardly. Above the plane 2 the bowl is distinctly non-symmetrical. This is because the section 12a is flared laterally as illustrated in Figs. 1 and 3. This enables the bowl to take material of large sizes, and to subject such large size material to crushing, whereby the material progresses downwardly and about the pestle for finer crushing. Note particularly that the bowl surfaces indicated generally at 47, which are relatively remote from the pestle in the region of plane 3, as well as surfaces designated generally by number 48 on the diagrammatically opposite side of the bowl, all perform crushing operations, and this is true for substantially the entire height of the bowl, above the plane 2. Thus the flaring section 12a of the bowl does not merely afford a convenient feed spout for the bowl, but actually forms crushing surfaces in cooperation with the pestle, for coarse crushing operations.

Reference has been made to the journal block 31, being adjustably carried by the base structure 10. One suitable mounting consists in forming a threaded engagement between the block 31, and the associated housing 49. The lower end of block 31 carries a depending stud shaft 51, upon which a sprocket 52 is splined. Housing 49 is carried by the webs 53, connecting the same with the main part of the base structure 10. The base structure is formed to afford an opening 54 extending to one side of the machine, and this opening can be used to accommodate a suitable means connecting with the sprocket 52, as for example a chain 56. Thus by manipulation of chain 56 sprocket 52 can be turned in either direction, to turn block 31, and therefore to raise or lower this block with respect to the base structure.

Operation of the machine described above can now be reviewed as follows: Fly wheel 17 is connected to an electric motor or other suitable 75 source of power, and also the drive wheel 38.

In general wheel 38 would be driven at a considerably higher speed, than the wheel 17. Block 31 is adjusted so that the clearance between the upper grinding face 36 of rotor 32, and the associate stationary grinding face 37, will afford the grind of a fineness desired. Also the position of the pestle 13 can be adjusted to deliver material of suitable fineness to the attrition mill, by adjusting the position of hand wheel 22. The ore or other material to be crushed is now supplied to the bowl, and particularly into the laterally flared section 12a, where it is crushed by the gyrating action of the pestle, and the crushed material permitted to drop downwardly through the bowl opening 57, to the rotor 32. Here the material is subjected to fine grinding by attrition, to be finally delivered downwardly through the openings 58, in the base structure. As previously pointed out the fineness of the grind can be adjusted by manipulation of 20 chain 56. Likewise the fineness of material supplied through the openings 51, can be adjusted by turning the hand wheel 22, which in turn raises or lowers the pestle with respect to the bowl. In the course of grinding operations the 25 pestle is more or less free floating. In other words it may raise against the spring 28, during the course of grinding operations or to pass an obstruction. When it is desired to clean the machine the bolts 43 are removed and the two sections 12a and 12b swung outwardly and downwardly, to the positions indicated in dotted lines in Fig. 1. Now the bowl, the pestle, and the rotor can all be cleaned, after which the two sections can be swung back into operating position and 30 clamped together by bolts 43. Because of the position of the bowl sections when they are swung down as illustrated in Fig. 1, the surfaces are accessible to ready cleaning and an operator can determine by quick visual inspection, the 35 presence of any remaining ore particles.

I claim:

1. In a crushing and grinding machine of the character described, a vertically extending spindle, a pestle journaled upon said spindle for free rotation relative thereto, a rotor of an attrition mill fixed to the lower end of said spindle below said pestle for rotation with said spindle, a bowl structure surrounding both the pestle and said rotor, said bowl structure having surfaces cooperating with said rotor for fine grinding operations, means for imparting gyroscopic movement to the upper end of the pestle and the associated spindle to also impart gyroscopic movement to the rotor of the attrition mill, said spindle having a center of oscillation adjacent the lower end thereof, and means for simultaneously applying turning movement to said spindle to thereby rotate the rotor of the attrition mill without applying like turning movement to the pestle.

2. In a crushing and grinding machine of the character described, a generally upright pestle, a spindle upon which the pestle is journaled for free rotation relatively to said spindle, a rotor of an attrition mill disposed below the pestle and secured to the lower extending end of the spindle for rotation with said spindle, a bowl structure cooperatively surrounding both the pestle and the rotor, said bowl structure affording crushing surfaces surrounding the spindle and surfaces cooperating with the motor for fine grinding, means for imparting gyroscopic movement to one end of the pestle and spindle to also impart gyroscopic movement to the rotor, said 75

spindle having a center of oscillation adjacent its other end and means for rotating the spindle whereby the rotor of the attrition mill is rotated about its axis independently of the positioning of the pestle with respect to the bowl structure.

5. In a crushing and grinding machine of the character described, a generally upright shaft or spindle, a pestle journaled upon the spindle for free rotation relative thereto, a rotor of an attrition mill secured to the lower end of said spindle below said pestle for rotation with said spindle, the upper grinding face of said rotor being substantially spherical, means for imparting gyratory movement to the upper end of the pestle and the associated spindle to also impart gyratory movement to said rotor, means for driving said spindle to effect independent rotation of said rotor, and a bowl structure surrounding the spindle and the rotor, said bowl structure affording surfaces cooperating with the pestle for crushing operations and also affording a substantially concave spherical shaped surface cooperating with the upper grinding face of the rotor, said spindle having a center of oscillation substantially coincident with the center of said spherical shaped surface.

4. In a grinding and crushing machine of the character described, a generally upright spindle, a pestle journaled upon the spindle for free rotation relative thereto, a rotor of an attrition mill secured to the lower end of said spindle below said pestle for rotation with said spindle, a portion of said spindle projecting below said rotor, the upper face of said rotor being spherical shaped and forming a grinding face, a base structure, means carried by the base structure, and forming a thrust bearing for the lower end of the spindle, means for imparting gyratory movement to the upper end of the pestle and to the associated spindle to also impart gyratory movement to said rotor, means for applying turning movement to the said spindle, whereby the rotor is turned about its axis, and a bowl structure cooperatively surrounding both the pestle and the rotor of the attrition mill, said bowl structure affording surfaces cooperating with the pestle for a crushing operation, and also affording a concave substantially spherical grinding face cooperating with the upper grinding face of said rotor, said thrust bearing forming a center of oscillation for said spindle and being located substantially at the center of said spherical grinding face.

5. In a grinding and crushing machine of the character described, a generally upright spindle, a pestle journaled upon the spindle for free rotation relative thereto, a rotor of an attrition mill secured to the lower end of said spindle below and spaced from said pestle for rotation with said spindle, a portion of said spindle projecting below said rotor, the upper face of said rotor being spherical shaped and forming a grinding face, a base structure, means carried by the base structure and forming a thrust bearing for the lower end of the spindle, means for imparting gyratory movement to the upper end of the pestle and to the associated spindle to also impart gyratory movement to said rotor, means for applying turning movement to the upper end of the shaft, whereby the rotor is turned about its axis, and a bowl structure cooperatively surrounding both the pestle and the rotor of the attrition mill, said bowl structure affording a surface cooperating with the pestle for crushing operations, and also a surface affording a con-

cave substantially spherical grinding face cooperating with the upper grinding face of said rotor, said surfaces extending between said pestle and rotor and said thrust bearing forming a center of oscillation for said spindle substantially at the center of said spherical grinding face and means for adjusting said rotor together with said spindle in a vertical direction.

6. In a gyratory crusher, a generally upright pestle, a rotor of an attrition mill disposed below the pestle, means for gyrating said pestle and for rotating the rotor of the attrition mill, a bowl structure surrounding both the pestle and the rotor of the attrition mill, said bowl structure having surfaces operating with the rotor of the attrition mill, to carry out fine grinding operations, and also including surfaces cooperating with the pestle to effect crushing, said bowl structure being split along vertical lines into two sections, a frame structure including a base and upright members adjacent the edges of said sections for positioning and reinforcing said sections, means for releasably clamping the vertical edges of said sections together and to said members, independent means serving to pivotally connect both said bowl sections to said frame structure, whereby said bowl sections, after releasing said clamping means, may be swung outwardly with respect to the pestle and the rotor of the attrition mill.

7. In a crushing and grinding machine of the character described, a generally upright pestle having a bulbular lower end, a spindle upon which the pestle is journaled for free rotation relative to said spindle, a rotor of an attrition mill disposed below and spaced from the pestle and secured to the lower end of the spindle for rotation with said spindle, a bowl structure for operatively surrounding both the pestle and the rotor, said bowl structure affording crushing surfaces surrounding the pestle and grinding surfaces cooperating with the rotor for fine grinding, said crushing surfaces and grinding surfaces extending into the space between said pestle and rotor, means for imparting gyratory movement to one end of the pestle and spindle to also impart gyratory movement to the rotor, means for rotating the spindle whereby the rotor of the attrition mill is rotated about its axis, said spindle having a center of oscillation adjacent its other end, means for adjusting said rotor with respect to said grinding surfaces of said bowl structure independently of the positioning of the pestle with respect to said crushing surfaces of the bowl structure, and means for adjusting the minimum clearance between the lower end of the pestle and the adjacent crushing surfaces of the bowl structure independently of the position of the rotor.

8. In a gyratory crusher, a generally upright pestle, means for gyrating said pestle, a bowl structure surrounding said pestle and cooperating with the pestle to effect crushing, said bowl structure being split along vertical lines into two sections, a frame structure including a base and upright members adjacent the vertical edges of said sections for positioning and reinforcing said sections, means for releasably clamping the edges of said sections together and to said members, independent means serving to pivotally connect both said bowl sections to said frame structure, whereby said bowl sections, after releasing said clamping means, may be swung outwardly with respect to said pestle.
